(57) **CLAIM**

The ornamental design for mount for a smart speaker as shown and described.

DESCRIPTION

FIG. 1 is a rear isometric view of the mount for a smart speaker showing the new design; the broken lines form no part of the claimed design;

FIG. 2 is a front isometric view of the mount for a smart speaker according to the invention;

FIG. 3 is a front elevation view of the mount for a smart speaker depicted in FIG. 2;

FIG. 4 is a right elevation view of the mount for a smart speaker depicted in FIG. 2;

FIG. 5 is a left elevation view of the mount for a smart speaker depicted in FIG. 2;

FIG. 6 is a top plan view of the mount for a smart speaker depicted in FIG. 2; and,

FIG. 7 is a bottom plan view of the mount for a smart speaker depicted in FIG. 2.

The broken lines shown in the drawings represent portions of the mount for a smart speaker that form no part of the claimed design.

1 Claim, 7 Drawing Sheets
